REFRIGERATOR.

Application filed April 4, 1927. Serial No. 180,640.

Our invention has for its object the provision of a refrigerator construction whereby an improved method of air circulation is obtained, a more adequate refrigeration or 5 cooling of the articles of food stuff provided; while at the same time contamination of certain food by reason of the presence of other articles in the refrigerator is prevented.

With our improved construction a more 10 uniform cold temperature of the entire food holding portion of the refrigerator is obtained and as a result a substantial equal chilling of all food stuffs is accomplished.

The objects and advantages of our invention 15 will all be readily understood from the detailed description of the drawings, wherein:

Figure 1 is a vertical sectional elevation 20 of our improved refrigerator.

Figure 2 is a detail sectional view of portions of the walls of a compartment, with an air directing element.

Figure 3 is a sectional view taken substantially on the line 3—3 of Figure 1, looking 25 in the direction of the arrows.

Figure 4 is a detail sectional view taken on the line 4—4 of Figure 1 looking in the direction of the arrows.

Figure 5 is a detail view in perspective 30 of the cold air flow regulating means.

Figure 6 is a vertical sectional view of a modified form of refrigerator involving our improvements.

In the exemplification, our invention has 35 been shown applied to a type of refrigerator more generally used in railroad dining cars wherein mechanical refrigeration is employed; although it will be equally applicable to refrigerators for commercial and 40 domestic use and wherein ice is employed as the cooling medium.

In Figure 1 we show a double type of refrigerator provided with our invention and consisting of the double walled receptacle or box 10, with the space between the walls filled with a suitable insulating material such as cork and the like.

The upper part of the refrigerator is shown provided with a mechanical refrigerating unit, generally shown at 11, of a well

known type involving fin coils 12; the unit being arranged in a compartment formed by the heavy walls 13 forming sides and bottom walls, which may be provided with insulation therebetween in order to prevent formation of condensate on the outer surface of said walls 13, and therefore prevent dripping into the food holding compartments therebeneath. The walls 13 are arranged in spaced relation with the main side wall 10 55 and also at top in spaced relation with the main top of the refrigerator; while the bottom portions of the walls 13 are preferably made sloping downwardly toward the vertical center of the refrigerator. The opposing lower ends of the bottom portions are spaced apart throughout the horizontal depth of the refrigerator in order to provide a horizontally elongated opening at 14, which 60 communicates with the upper end of a cold air duct 15 which leads to the bottom of the refrigerator and extends from front to rear of the refrigerator. The bottom portions of the walls 13, adjacent to the opening 14 are each shown provided with an upstanding lip 65 or flange 16 for the purpose of preventing dripping of the condensate into the cold air duct 15; and for that reason a shield or baffle plate 17 is arranged above the opening 14, extending throughout the length of said 70 opening; the shield sloping toward opposite sides of the vertical center and to points beyond the vertical planes of the lips or flanges 16.

Where a mechanical refrigerating unit is 75 employed, the copper tubes, as shown at 18, are carried downwardly to the bottom of the refrigerator where they unite. As the refrigerating unit forms no part of our invention, a more detailed description of its construction and operation need not be entered 80 into; it being understood that ice or any other cooling medium may be employed.

The refrigerator beneath the refrigeration element holding compartment formed by 95 walls 13 is provided with a series of independent compartments formed by the walls 19 and 20, of any suitable material, as for example sheet metal, extending from front to rear of the refrigerator.

In the large or double type refrigerator shown in Figure 1, the walls 19, 19 are arranged in spaced relation to provide the cold air duct or passage 15; while the walls 20, 20 are arranged in spaced relation with the side walls of the refrigerator proper so as to provide the two warm air ducts 21, 21 which extend from the main bottom of the refrigerator to the top of the compartment walls 13 and communicate with the refrigerating medium holding compartment by the passages 22. The walls 19 and 20 preferably terminate a slight distance above the main bottom of the refrigerator so as to leave the passages 23 in order that complete circulation beneath the lowermost compartments may take place; the passages 23 providing communication between the cold air duct 15 and the warm air ducts 21. The side walls 19 and 20 at suitable predetermined points are formed to support the solid plate trays or shelves 24, which may be permanently or removably secured in place. As the walls 19, 20 and trays or shelves 24 extend from front to rear of the refrigerator, it is apparent that a plurality of separate non-communicating compartments are provided adapted to separately hold various food articles and each providing a separate chilling chamber.

The side walls 19, preferably at points coincident with the upper ends of the separate food holding compartments, are shown formed with the upwardly and outwardly bent portions 25 which extend into the cold air duct 15.

In the exemplification, the walls 19, 20, like the trays or shelves 24, are shown made of sheet metal, so that the lips or portions 25, shown integral with the side walls 19, may be flexed to the desired angle found necessary for different uses and temperature conditions of any particular refrigerator or any particular compartment.

In order to maintain the desired angularity of the lips or portions 25, one or both ends of the lip or portion 25 is shown provided with a flange 26, disposed adjacent to a wall of the refrigerator; and this flange 26 provided with a slot as at 27 to receive a set-screw 28. After the lips 25 have been bent outwardly to the desired extent, the set-screw 28 is tightened so as to maintain the proper angularity of the lip. Of course, it is apparent that the lips need not be an integral part of the side walls 19, but that they may be hingedly connected thereto, as the set-screw 28 will maintain the proper regulated position.

The opposite side walls 20 of the respective compartments at points adjacent to the tops of the different compartments are likewise provided with the outwardly bent portions or lips 29, substantially identical with the lips 25 and preferably secured in their adjusted positions by set-screws 28.

With the compartments extending from the

rear wall of the refrigerator to the front where the doors (not shown) close the front sides and having the solid side walls 19, 20 and solid bottoms or shelves 24, it is apparent that the only points of communication 70 between the respective compartments and the remainder of the refrigerator are through the openings in the side walls 19, 20 formed by the outwardly disposed partially severed side wall portions 25, 29.

The chilled air from the refrigerating medium holding compartment in the upper end of the refrigerator flows through the bottom opening 14 downwardly in the cold air duct 15. With the lips or louvers 25 sloping 80 upwardly and outwardly into the cold air duct 15, it is evident that cold air will flow through the opening at the top of each food holding compartment and flow or drop toward the shelf 24 constituting the bottom of a compartment and hence be caused to pass over and about the various food-stuffs in said compartment; while the displaced or warm air in the respective food holding compartment will rise toward the top at the opposite side 90 wall 20 and be discharged through the opening formed by the outwardly sloping portion 29 into the adjacent warm air duct 21. The warm air in the ducts 21 will rise toward the top of the refrigerator and pass through the opening 22 at the upper end of the compartment forming wall 13 and be discharged into contact with the refrigerating medium and thereby chilled and made to flow through bottom opening or throat 14 into the cold air 95 duct 15. With the double or heavy walls 13, the rising air in the warm air ducts when passing adjacent to the walls 13 will not be chilled until it enters the chilling medium holding compartment, so that proper upward circulation in the ducts 21 will not be interfered with, but on the other hand a constant circulation of air will be maintained.

In order to induce a sufficient amount of cold air to enter the respective food-stuff holding compartments, we provide the bottom of the cold air duct 15 with a back-pressure creating or baffle means in the nature of a perforated element shown at 30 supported in a suitable manner,—as for example by the flanges 31 on the side walls 19,—at a proper distance, say about six inches or so above the bottom of the refrigerator. In the exemplification, this element 30 is shown as consisting of two superposed perforated plates 30^a—30^b (see Figure 5) slidably secured together or so arranged that a complete or partial registration of the perforations in the two plates may be had, for the purpose of regulating the size of the air holes and thereby controlling the desired or necessary amount of back-pressure in the cold air duct 15 to meet varying conditions and hence giving greater flexibility or adaptability of the refrigerator to the many different operating en- 110 115 120 125 130

vironments. It is apparent that by regulating the angularity of the lips 25 and the size of the openings in back-pressure element 30, the degree of cold air flow into and chilling of the respective food holding compartments may be controlled in keeping with the contents of the respective compartments. Our improved refrigerator permits each shelf or compartment bottom 24 to be completely covered with food without hindering proper circulation of air.

The bacteria, at least a large percentage thereof, is eliminated from the air by reason of the condensation of the bacteria carrying moisture in the chilled portion of the refrigerator and is either deposited on the fins, where mechanical refrigeration is used, or collects on the baffles and is drained off with the other moisture where ice is used as the refrigerant. Hence contamination of different food-stuffs, by reason of the separate compartments, is not possible.

The outwardly bent portions or lips 25 and 29 may extend continuously, from front to rear of the respective compartments or they may be in separate similar sections as shown more clearly in Figure 4.

The refrigerating medium compartment is provided with a drain tube as at 32, see Figure 3, which may be adjacent to the rear wall of the refrigerator; the bottom of the compartment having a slight downward slope toward the rear to induce proper drain.

In Figure 6 we have incorporated our novel features in a smaller or single type of refrigerator, namely a refrigerator with but a single tier of compartments and therefore consisting of one half or side of the refrigerator shown in Figure 1. In Figure 6, 33 represents one of the main walls of the refrigerator, the refrigerating element or unit 11 being in the top compartment formed by the main refrigerator walls and the inner double wall 13^a arranged in spaced relation with the other main wall 34 of the refrigerator and formed to provide the passage 22^a at top which establishes communication between the refrigerating compartment and the warm air duct 21^a adjacent the wall 34 of the refrigerator and 50 extending upward from the bottom thereof, the same as in Figure 1. The bottom of wall 13^a slopes downwardly toward the side wall 33 terminating a slight distance therefrom to permit the chilled air to flow down through the cold air duct 15^a formed between the wall 33 of the refrigerator and the wall or partition 19^a which is similar to wall 19 in Figure 1. The food holding compartments like in Figure 1 are formed by the solid walls or partitions 19^a, 20^a and the solid sheet shelves 24^a, thus providing independent non-communicating compartments each having communication with the remainder of the refrigerator merely through the openings formed at the tops of the respective food-holding compart-

ments by the outwardly flexed portions or bent lips 25^a and 29^a formed in the walls or partitions 19^a and 20^a, respectively. The cold air passes into each compartment through the openings formed by the lips 25^a, while the warmer air passes out from the compartments through the openings formed by the lips 29^a. The bottom of the cold air duct 15^a is also shown provided with a back-pressure producing element 30 arranged a suitable distance above the bottom of the refrigerator, like in Figure 1.

The exemplifications of the invention as disclosed in the drawings have in practice produced the desired results and possess the advantages set forth, especially for dining car refrigeration, but modifications in certain details of construction may be made without, however, departing from the spirit of our invention, which has been described in terms employed merely as terms of description and not as terms of limitation.

What we claim is:

1. A refrigerator provided with a refrigerant-holding compartment in the upper end thereof, food-stuff holding compartments arranged in a vertical tier beneath, all of said compartments having solid sides and bottom walls, the bottom of the refrigerant-holding compartment having an opening, an air duct leading from said opening downwardly along a side wall of the food-stuff holding compartments and open at the lower end of the refrigerator, a warm air duct leading from the bottom of the refrigerator adjacent the opposite side wall of the food-stuff holding compartments and communicating with the upper end of the refrigerant-holding compartment, an air passage beneath the lowermost food-stuff compartment communicating with the lower ends of both air-ducts, the side walls of the food-stuff holding compartments coincident with the upper ends thereof having openings, and adjustable portions secured at the lower ends of the openings and sloping upwardly outward into both of said ducts, for inducing direct inflow of cold air from the cold air duct into each of said food-stuff holding compartments and for effecting education action at the outlet openings of each of said chambers.

2. A refrigerator provided with insulated outer walls and comprising inside vertically disposed solid partitions arranged in spaced relation with the main walls of the refrigerator, imperforate shelves arranged at predetermined points between and supported by the partitions whereby non-communicating chambers are provided, one of said chambers constituting a refrigerant holding chamber while the others constitute food-stuff receiving chambers, air ducts disposed vertically adjacent to the partitions at opposite sides of the food-stuff holding chambers and in communication with each other at the bottom

of the refrigerator beneath the lowermost food-stuff receiving chamber, one of said ducts being connected with the bottom of the refrigerant holding chamber and constituting a cold air duct while the other duct communicates with the upper end of the refrigerant holding chamber and constitutes a warm air duct, the partitions adjacent to the upper parts of the food-stuff chambers having openings, adjustable lips secured to the partitions for regulating the openings, said lips sloping upwardly outward into the air ducts for inducing direct flow of cold air from the cold air duct into each of the food-stuff chambers and for effecting eduction action at the outlet openings of each of said chambers, and a pair of superposed perforated plates arranged at the lower end of the cold air duct above the bottom of the refrigerator and in advance of the point of communication between the lower ends of said air ducts, said plates being slidable relative to each other whereby the extent of registration of the perforations in both plates may be altered and the speed of outflow at the bottom of the cold air duct regulated.
